SUCTION CLEANER HAVING ADJUSTABLE
NOZZLE WITH CONVERTER AND HAN-
DLE INTERLOCKGeorge E. Kaufman, Canton, Ohio, assignor to
The Hoover Company, North Canton, Ohio, a
corporation of Ohio

Application May 14, 1951, Serial No. 226,148

17 Claims. (Cl. 15—333)

1

My present invention relates to the art of suction cleaners and has for its principal objects the provision of a nozzle position control, handle interlock and dusting tool converter embodying some or all the features and relations set forth hereinbelow.

According to my invention, a foot pedal, or other operator actuated means, is provided for shifting the suction nozzle to a high cleaning position and the nozzle is returned to normal cleaning position each time the propelling handle is placed in a predetermined position such as the upright storage position. The nozzle shifting mechanism and handle include means which bar the insertion of a dusting tool converter unless the handle is in the aforementioned predetermined position in which case the converter actuates the mechanism to place the nozzle in non-cleaning position and to lock the handle in the said predetermined position. When the converter is withdrawn, the nozzle automatically returns to normal cleaning position and the handle is unlocked to allow normal pivotal movement of the handle on the cleaner body.

Other objects and advantages of the invention will become apparent as the description proceeds when taken in connection with the accompanying drawings, in which

Figure 1 is a side sectional view of a suction cleaner embodying my invention taken along the lines 1—1 of Figures 2 and 3 and looking in the direction of the arrows;

Figure 2 is a partial plan view in section along the line 2—2 of Figure 1 and looking in the direction of the arrows;

Figure 3 is a partial elevational view in section along the line 3—3 of Figure 1 and looking in the direction of the arrows;

Figure 4 is a side elevational view of the cleaner with parts omitted showing the control and handle interlock mechanism with the nozzle adjusted for high cleaning position; and

Figure 5 is a view similar to Figure 4 showing the apparatus converted for dusting tool operation.

Referring now to the drawing in detail and first to Figure 1 thereof I have illustrated a suction cleaner comprising a main casting 1 provided with a surface cleaning nozzle 2 across the front thereof in which is rotatably mounted a surface agitating and brushing device 3. The main frame of the cleaner is provided with a fan chamber 4 within which is mounted a centrifugal suction fan 5 carried by the shaft of an electrical drive motor 6 mounted on the top of the frame 1.

2

The fan has a hub portion 7 extending through an air inlet opening 8 in the casing 4. The hub portion 7 terminates in a drive pulley 9 positioned in an air duct 10 extending from the suction inlet 8 of the fan 5 to the nozzle 2. A drive belt 11 extends between the pulley 9 and the rotary agitating device 3 for driving the device 3 from the motor 6. The fan chamber 4 is provided with a discharge passage 12 which communicates with an exhaust elbow 13 for conveying dirt laden air to a filter mechanism.

The handle mount, filter and filter elbow support mounting illustrated herein is substantially the construction disclosed and claimed in the co-pending application to Werner G. Seck, Serial No. 200,391, filed December 12, 1950. Essentially this mechanism consists of the elbow 13 which swivels on a journal formed around the outlet of the cleaner exhaust passage 12 on one side and upon 15 a pin 14 which is swivelled in a bushing 15 carried by an upstanding pillar 16 projecting from a rearwardly extended section 17 of the main casting 1.

The cleaner propelling handle 20 seats in a 25 socket member 21 carried by a split handle supporting bail 22. One leg of the bail 22 is journaled on the outlet portion of the exhaust duct 12 in a manner such as that disclosed in the aforesaid co-pending application. The other leg of the bail 22 is journaled on the pin 14 and is held in abutting relation to the bushing 15 by a spacer collar 23 which abuts the pin mounting portion of the elbow 13. A locking plate 25 is secured by means of rivets 26 to the portion of the bail arm 22 which pivots on the pin 14. The plate 25 is also pierced by the pin 14 as is apparent from Figures 1 and 2. The upper portion of the exhaust elbow 13 is provided with a cylindrical section 28 which receives the mouth portion of a filter 29, preferably of paper. A clamping wire 30 is provided for securing the filter 29 to the tubular member 28. The filter 29 is encased in an appearance bag 31, preferably of fabric, which is closed at one side by means of a slide fastener 32. The upper end of the filter assembly 30 may be connected to the upper portion of the handle 20 in a known manner.

The rear of the cleaner body is supported by a pair of caster wheels 34 each of which is supported on a stub shaft 35 carried by a downwardly projecting arm 36 on the rearwardly extending portions 17 of the main casting 1. The forward portion of the cleaner is supported by wide tread large diameter wheels 38 carried by an 50 axle 39 having its central portion 40 offset from

the wheel axes by crank arms 41 as is illustrated most clearly in Figures 1 and 2. The central portion 40 of the axle 39 lies in a pivoting groove 42 in the upper face of the main frame 1 and is secured thereto by anchoring plates 43 joined to the main frame 1 by studs 44. It is apparent that pivotal movement of the axle 39 in the groove 42 raises and lowers the wheels 38 with respect to the body portion of the cleaner and will raise and lower the nozzle 2 with respect to a supporting surface upon which the wheels 38 are resting. A flanged collar 45 is rotatably supported upon the shaft 39 adjacent the wheel 38 on the right hand side of the cleaner facing forwardly thereof. The collar 45 bears upon the edge of an adjusting cam 46 which is pivotally mounted upon a stud 47 carried by the side wall of the fan housing 4. The cam 46 is provided with positioning notches 49, 50 and 51. The central notch 50 is closest to the stud 47, thus allowing the wheels 38 to swing into the cleaner body to a maximum distance and to lower the nozzle 2 to its closest approach to the supporting surface. The notch 50 locks the wheels 38 in the normal cleaning position. When the cam 46 is shifted on its axis to engage the notch 49 with the collar 45, the axle is rotated a short distance counter-clockwise, as viewed in Figure 1, which raises the nozzle to a high cleaning position for thick carpets and the like. When the cam 46 is rotated to engage the notch 51, with the collar 45, the wheels 38 are rotated a still greater distance counter-clockwise, as viewed in Figure 1, to raise the nozzle to its maximum non-cleaning position which also raises the rotary agitator 3 above surface engaging position. The notches 49 and 50 are separated by deep shoulders so that some positive action is required to shift the cam 46 to engage these notches with the shaft collar 45. The surface 52 separating the notches 50 and 51 is an arc of a circle drawn about the center of the stud 47 wherefor only a slight force is required to rock the cam to remove the notch 51 from the collar 45 and to engage the notch 50 with the collar. The reverse operation cannot be accomplished without applying an appreciable force to the cam because of the steep sides of the notch 50. A tension spring 53, connected between the axle 39 and the stud 47, biases the axle 39 in a clockwise direction, as viewed in Figure 1, to maintain the collar 45 in firm engagement with the cam 46 under normal operating conditions.

A pivoted spring-closed gate 55 normally blocks communication between the duct 19 and a rearwardly and downwardly inclined passageway 56 which is part of the main frame 1. The passageway 56 extends rearwardly and downwardly on the center line of the machine and its side walls are spaced inwardly of the pivot point of the handle bail as shown most clearly in Figure 2. The passageway 56 is joined to the rearwardly projecting section 17 of the main frame by a transverse plate 57 positioned just rearwardly of the fan casing 4. The outer end of the passageway 56 is joined by a plate 58 to one leg of a U-shaped pedal supporting member 59. The other leg of the member 59 is integral with the section 17 of the main frame and depends directly beneath the handle support 16.

The positioning cam 46 connects to a drag link 60 which in turn is connected to one leg of a U-shaped locking link 61. The legs of the locking link are pivotally supported by a pin 62 carried by a pair of supporting post members 63.

projecting rearwardly from the plate 51. The bright portion 64 of the link 61 is positioned to rock over a horn member 65 projecting forwardly from the locking plate 25 when the handle is in the vertical storage position illustrated in Figure 1 for a purpose to be developed more fully hereinafter.

The leg of the U-shaped link 61 to which link 62 connects is provided with a rearwardly extending section 66 which carries a short pin 67 engaging in an open-ended slot 68 in the outer end of one leg of a U-shaped pedal member 69. The pedal 69 is pivotally mounted upon a pin 70 carried by the leg portions of the U-shaped 15 supporting member 59. The pedal 69 has a foot engaging tread section 72 extending beyond the rear boundaries of the cleaner frame, as shown most clearly in Figures 1 and 2. A torsion spring 74 is mounted on the pin 70 and has extending 20 end portions bearing on the bight portion of the pedal 69 and support member 59 to bias the pedal in a counter-clockwise direction as viewed in Figure 1.

Assuming the parts occupy the positions illustrated in Figure 1, it is apparent that a downward pressure applied to the tread portion of the pedal 69 will rock the pedal in a counter-clockwise direction which, through the engagement of the pedal with the pin 67, will rock the lever 61 in a clockwise direction which will impart a forward thrust to the drag link 68 and will rotate the cam 46 counter-clockwise to engage the high cleaning position notch 49 with the collar 45 on the wheel axle to raise the nozzle 30 to position the parts as they are shown in Figure 4. As long as the handle is in the storage position shown in Figure 1, the foregoing action is prevented by a pin 13 carried by the locking plate 25 overlying and engaging an upwardly extending portion 74 on the inner leg of the pedal 69. When the handle is dropped to operative, propelling position, the pin 13 pivots away from engagement with the member 74 and the pedal may be operated as desired.

45 It is apparent from Figure 4 that raising the handle to the upright storage position illustrated in Figure 1 will rock the pin 73 into engagement with the member 74 which will rotate the pedal 69 in a clockwise direction in turn rotating the link 61 and control cam 46 to disengage the notch 49 and engage the normal cleaning position notch 50 with the collar 45. That is, every time the handle of the cleaner is placed in storage position; it operates upon the nozzle position control mechanism to place the same in the normal cleaning position if these parts do not already occupy that position.

The inner leg of the locking link 61 is provided with a depending portion having an angularly bent lateral extension 76 extending through an opening 77 in the adjacent side wall of the converter passageway 56. The lateral extension 76 acts as a barrier to prevent the insertion of a converting tool into the passageway 56 as is apparent from Figures 1 and 3 and as a cam to be actuated by a converting tool 83, see Figure 5, to place the nozzle 2 in a very high non-cleaning position. Referring now to Figure 5, the condition of the parts is illustrated when a dusting tool converter 80 is in operative position. The converter member 80 has an elongated portion 81 shown within the passageway 56 and sealing across the inlet opening 6 to the fan chamber.

In the position of the parts shown in Figure 1, the barrier cam 16 presents an inclined surface

to the entrance to the passageway 56 at the bottom thereof whereby insertion of a converting tool into the passageway 56 will cam the barrier 76 below the passageway 56 to rock the link 61 counter-clockwise and the cam 46 clockwise. Such rotation of the link 61 and cam 46 will pass the bar 64 over the horn 65 to lock the handle in storage position and will engage the notch 51 with the collar 45 to place the nozzle in a high, non-cleaning position of Figure 5. If the handle is not in the position of Figure 1, the arcuate surface 27 on the plate 25 lies in the path of movement of the bar 64 to prevent counter-clockwise rotation of the link 61 which action also prevents insertion of the converter because the barrier 76 cannot be moved out of the passageway 56. When the nozzle is in the high cleaning position of Figure 4, the barrier cam 78 is in the top of the passageway 55 and cannot be actuated by the converter. The cleaner is changed from the high cleaning position of Figure 4 to the normal position of Figure 1 by moving the handle to storage position which action restores the parts to normal cleaning position. It is apparent from the foregoing that the converting tool 80 can be inserted only when the handle is in storage position and that the handle is locked in such position as long as the converter is inserted. The pedal 69 cannot be actuated to control the nozzle position when the converter is inserted because the barrier cam 78 engages the converter 80 and prevents counter-clockwise rotation of the link 61.

The converting tool 80 can be inserted by forcing the same into the passageway 56 when the cleaner is resting upon the floor with the parts in the position illustrated in Figure 1, but the application of the tool is much simpler if the handle is first raised to a storage position and used to rock the cleaner upwardly and forwardly upon the front edge of the nozzle to remove the wheels 38 from engagement with the floor. When this procedure is followed, the open end of the passageway 56 is facing upwardly and rearwardly where it is readily accessible and the camming action between the surface 75 and the converter tool 80 is required only to overcome the friction of the parts and the tension of the springs 53 and 71.

Immediately the converter tool 80 is withdrawn from the passageway 56, the spring 71 rocks the pedal 69 in a counter-clockwise direction which acts through the links 60 and 61 to rotate the cam 46 counter-clockwise to return the normal cleaning position notch into engagement with the collar 45. The spring 71 has sufficient strength to perform this function because the surface 52 is an arc about the axis of rotation of the control cam. Hence rocking movement of the cam 46 in this direction does not act against the tension of the wheel positioning spring 53 until the axle drops into the notch 50 after which the spring 71 is too weak to impart further movement to the cam 46.

The converting tool 80 is provided with a spring 65 latch structure 82 adapted to engage with a hooked end 83 on the bottom wall of the passageway 56 to secure the converting tool in the passageway 56 against accidental displacement.

The present invention provides a suction cleaner support in which the handle actuates the nozzle to normal cleaning position whenever the handle is moved to storage position, the handle must be in storage position before a converter can be applied to the cleaner and the handle is locked 75

in storage position when a converter is applied to the cleaner. In addition, a pedal is provided for moving the nozzle to a high cleaning position unless barred by the handle being in storage position and the converter actuates the nozzle to a non-cleaning position from which the nozzle returns automatically to normal position when the converter is withdrawn.

I claim:

1. Suction cleaning apparatus comprising a frame including a suction nozzle, wheels for supporting said frame on a surface to be cleaned, means mounting certain of said wheels on said frame for movement toward and away from said frame to adjust said nozzle relative to a surface being cleaned, means for moving said mounting means to adjust said nozzle, a propelling handle pivotally mounted on said frame, means on said handle for operating said moving means to adjust said nozzle to a predetermined position when said handle is moved to a pre-selected position, means forming a passage for the insertion of a tool for converting the apparatus for off-the-surface cleaning, means carried by a part of said moving means extending into said passage to block insertion of such converting tool and having a cam surface to be engaged by such tool to be moved out of such passage by such tool and to operate said moving means to raise said nozzle to a non-surface engaging position, and means on said handle for barring operation of said moving means to raise said nozzle to said inoperative position when said handle is in any position other than said pre-selected position.
2. Suction cleaning apparatus comprising a body having a suction nozzle thereon, wheels for supporting said body upon a surface being cleaned, means for moving certain of said wheels relative to said body to vary the position of said nozzle relative to said surface, pedal operated means for actuating said moving means to place said nozzle in a high cleaning position, a propelling handle pivotally mounted on said body, means on said handle for actuating said moving means to place said nozzle in a normal cleaning position when said handle is placed in a predetermined position, means for actuating said moving means to raise said nozzle to an inoperative, non-cleaning position, and means on said moving means for latching said handle in said predetermined position when said nozzle is placed in said inoperative position.
3. Apparatus according to claim 2 including means on said handle for barring movement of said nozzle to said inoperative position when said handle is not in said predetermined position.
4. In a suction cleaning cleaner having a suction producing unit connected by an air duct to a surface cleaning nozzle and having a passageway for guiding a converting tool into said air duct, the combination of means supporting the rear of said cleaner, an axle pivoted to the front of said cleaner having offset portions, supporting wheels on said offset portions of said axle, means for positioning said wheels relative to said cleaner to adjust the position of said nozzle relative to a supporting surface comprising a stop having first and second cleaning positions and a non-cleaning position, a foot pedal connected to actuate said stop from said first to said second position, means for moving said stop from said non-cleaning position to said first position, a propelling handle pivotally mounted on said cleaner, means operated by movement of said handle to a predetermined position for operat-

ing said stop from said second position to said first position, and means operated by insertion of a converting tool into said passageway for moving said stop to said non-cleaning position and for barring operation of said means for moving said stop from said non-cleaning position.

5. Apparatus according to claim 4 including means on said handle for barring operation of said stop to said non-cleaning position when said handle is not in a predetermined position.

6. Apparatus according to claim 5 including means for locking said handle in said predetermined position when said stop is in said non-cleaning position.

7. In a suction cleaner having a suction producing unit connected by an air duct to a surface cleaning nozzle and having means forming a passageway for guiding a converting tool into said air duct, the combination of means for supporting such cleaner upon a surface, means for changing the position of said supporting means relative to such cleaner to adjust the position of said nozzle relative to a supporting surface, means operated by insertion of a converting tool for actuating said position changing means to place said nozzle in a non-cleaning position, a propelling handle pivotally mounted on said cleaner, means on said handle for barring operation of said position changing means by a converting tool when said handle is not in a predetermined position, and means on said position changing means for locking said handle in said predetermined position when said nozzle is in said non-cleaning position.

8. Apparatus according to claim 7 including means for actuating said position changing means to unlock said handle to place said nozzle in a normal cleaning position when said converting tool is withdrawn from said passageway.

9. In a suction cleaner having a body provided with a surface cleaning nozzle, an air duct communicating said nozzle with a suction producing means on said body, a propelling handle pivotally mounted on said body, and a passageway for guiding a converting tool into said air duct, the combination of means for supporting the rear of said body upon a surface to be cleaned, an axle pivotally mounted on said body adjacent the front thereof and having end portions offset from the pivotal axis thereof, wheels carried by said end portions for supporting the front of said body on a surface to be cleaned, a cam, means pivotally supporting said cam on said body, means biasing one of said end portions into engagement with said cam, said cam having notches therein positioned to be moved into engagement with said one end portion by pivotal motion of said cam to one position said nozzle selectively in high or normal cleaning position or in non-cleaning position, an operating member for said cam pivotally mounted on said body, means connecting said operating member and said cam for imparting movement of said operating member to said cam, a foot pedal on said body member connected to said operating member to actuate said cam to place said nozzle in high cleaning position, means on said handle for actuating said pedal when said handle is placed in a predetermined position to place said nozzle in normal cleaning position, and a cam arm on said operating member extending into said passageway to be operated by the insertion of a converting tool to pivot said operating member and said cam to place said nozzle in said non-cleaning position.

10. Apparatus according to claim 9 including

means on said handle barring movement of said operating member by said cam arm to place said nozzle in said non-cleaning position when said handle is not in said predetermined position.

11. Apparatus according to claim 9 including cooperating locking means on said handle and said operating member engageable when said handle is in said predetermined position and said nozzle is in said non-cleaning position to prevent pivotal movement of said handle.

12. In a suction cleaner having a body provided with a surface cleaning nozzle, a suction producing means on said body, an air duct extending from said nozzle to said suction producing means, a propelling handle pivotally attached to said body and means forming a passageway for guiding a converting tool into said air duct, the combination of means for supporting said body, means for moving said supporting means relative to said body to adjust the position of said nozzle relative to a supporting surface, mechanism for actuating said moving means having an operating part extending into said passageway to be operated by the insertion of a converting tool to operate said moving means to place said nozzle in a non-cleaning position, and means on said handle normally lying in the path of movement of a portion of said actuating mechanism to bar insertion of a converting tool and movable out of said path of movement of said portion of said actuating mechanism by movement of said handle to a predetermined position.

13. Suction cleaning apparatus comprising a body member having a suction nozzle, suction producing means on said body, means forming an air duct from said nozzle to said suction producing means, means forming a passageway for the insertion of a conversion tool into said duct, supporting wheels for said body, means for moving certain of said wheels relative to said body to adjust the position of said nozzle relative to a supporting surface, said moving means including a part extending into said passageway into the path of a converting tool normally barring entry of such tool into said passageway, said part including a cam surface engageable by such tool to move said part from said passageway and to operate said moving means to place said nozzle in a non-cleaning position, a propelling handle pivotally mounted on said body, and means on said handle barring operation of said moving means by said cam surface to place said nozzle in said non-cleaning position when said handle is not in a predetermined position.

14. Apparatus according to claim 13 including means on said handle and said moving means for locking said handle in said predetermined position when said nozzle is in said inoperative position.

15. Apparatus according to claim 13 including a foot pedal for operating said moving means to place said nozzle in a first cleaning position, and means on said handle for operating said moving means to place said nozzle in a second cleaning position when said handle is moved to said predetermined position.

16. Apparatus according to claim 15 including means for operating said moving means to place said nozzle in said second position when such tool is removed from said passageway.

17. In a suction cleaning apparatus having a suction producing unit connected by an air duct to a surface cleaning nozzle, means forming a passageway for guiding a converting tool into said air duct, and a pivotally mount-

ed propelling handle, the combination of means including a movable member for varying the position of said nozzle relative to a surface to be cleaned, operator operated means for actuating said movable member to place said nozzle in a first cleaning position, means actuated by movement of said handle to a predetermined position for actuating said movable member to place said nozzle in a second cleaning position, means on said movable member extending into said passageway and movable out of said passageway by insertion of a converting tool into said passageway to actuate said movable member to place said nozzle in a non-cleaning position, and means on said handle barring movement of said movable means to place

10 said nozzle in said non-cleaning position when said handle is not in said predetermined position whereby said means in said passageway normally prevents insertion of a converting tool into said passageway.
